APPARATUS FOR ATTACHING HEELS TO SHOES

Edward F. Small, Newton, Mass., assignor to
Compo Shoe Machinery Corporation, Boston,
Mass., a corporation of Delaware

Application September 7, 1946, Serial No. 695,431

8 Claims. (Cl. 12—42)

1

This invention relates to the securing of heels to shoes and more particularly to an apparatus for attaching heels to shoes mounted upon lasts having fastener receiving recesses therein.

Heretofore, it has been general practice to secure heels to shoes, mounted upon lasts having fastener receiving recesses therein, by clamping the heel to the shoe, with or without an adhesive interposed therebetween, and then driving a nail or drive screw, via the recess in the last, into the heel seat of the shoe and into the heel clamped thereto. Such procedure is rather costly since very often the nail or drive screw splits the heel and thus the heel must be replaced and the operation again performed.

It also has been general practice to secure heels to shoes mounted on lasts having fastener receiving recesses therein, by clamping the parts together, inserting a drill into the fastener receiving recess of the last to drill a lead hole into the located heel to receive a wood screw, and thereafter inserting a screw driver into the last recess to drive a wood screw into the heel to effect securing of the heel to the shoe. Carrying out of this method is also costly, since a somewhat complicated machine having two spindles is required and operation thereof is comparatively slow as either the spindles or the shoe and heel must be moved after the drilling operation to allow entry of the screw driving spindle. Furthermore, the drills used to bore the lead holes for the wood screws must, of necessity, be slender and they frequently break or become dull causing added expense and delay.

A general object of this invention is to provide an improved method of securing heels to shoes by means of wood screws, while the shoes are mounted upon their original lasts, which reduces the cost of such operation while increasing the output of work.

Another object of the invention is to provide a method of securing a heel to a shoe in a manner which allows the wood screw used to effect the securing of the heel to the shoe to form its own lead hole into the heel to be secured, and which obviates the use of a separate drilling operation.

A further object of the invention is to provide a machine for securing a heel to a shoe, which has but a single spindle to form a lead hole into the heel to be secured and to drive a wood screw into such heel.

A still further object of this invention is to provide an improved machine for securing heels to shoes, by means of wood screws, which is con-

2

structed and arranged in a manner to carry out my improved method in a rapid and efficient manner.

Other objects of the invention will in part be obvious and will in part appear hereinafter.

The invention accordingly comprises of several steps and the relation of one or more of such steps with respect to each of the others, and the apparatus embodying features of construction, combination of elements and arrangement of parts which are adapted to effect such steps, all as exemplified in the following disclosure, and the scope of the invention will be indicated in the claims.

15 For a fuller understanding of the nature and objects of the invention reference should be had to the following detailed description taken in connection with the accompanying drawing, in which:

20 Fig. 1 is a sectional side elevation of a heel attaching machine embodying features of my invention and showing a shoe and heel clamped together in position to receive the action of the machine;

25 Fig. 2 is a sectional front elevation of the machine, taken substantially along line 2—2 of Fig. 1;

Fig. 3 is a partial plan view taken substantially along line 3—3 of Fig. 1;

30 Fig. 4 is a fragmentary front elevation of the machine, partly in section, and showing the spindle about to be reciprocated to cause the wood screw to bore a lead hole into the heel clamped to the shoe;

35 Fig. 5 is a view similar to Fig. 4 but showing the spindle partially advanced towards the heel and the lead hole formed into the heel;

Fig. 6 is another view similar to Figs. 4 and 5 but showing the spindle retracted, the lead hole completely bored into the heel, and the spindle about to be reciprocated to drive the wood screw into final engagement with the heel and shoe;

40 Fig. 7 is a fragmentary view on an enlarged scale, of a portion of Fig. 6;

Fig. 8 is a view similar to Fig. 6 but showing the spindle advanced to its upper limit and the wood screw driven to its final position to attach the heel to the shoe;

45 Fig. 9 is a fragmentary view, on an enlarged scale, showing the condition of the screw according to Fig. 8, and also showing the spindle after rotation thereof has been reversed to disengage it from the wood screw;

50 Fig. 10 is a fragmentary sectional view of the

spindle showing an alternative method of securing the wood screw thereto; and

Fig. 11 is a schematic wiring diagram of the driving motor and its controls.

My novel method of securing a heel to a shoe mounted upon a last having a fastener receiving recess therein comprises the following simple steps, clamping the heel to the heel seat of the shoe, inserting a screw within the fastener receiving recesses of last and rotating the screw in a screw driving direction while advancing the screw into the heel seat of the shoe and into the heel at a rate which is less per revolution of the screw than the lead of the screw thread until a lead hole is bored into the heel to a depth equal to approximately one-half of the length of the screw, withdrawing the screw from the hole formed in the heel in order to clear the chips from the screw and the hole, and thereafter again advancing the screw towards the heel until the screw enters the lead hole formed therein and the screw thread engages with the heel material and the screw is driven to its final depth to allow the head of the screw to clamp the heel seat of the shoe to the heel.

This method greatly reduces breakage of heels and can be carried out in a rapid and efficient manner with the aid of simple hand operated tools (not shown) or with a power operated machine of the type hereinafter described.

Referring to the drawings and first to Figs. 1 and 2, there is shown a machine for attaching heels to shoes which comprises a frame casting 10 having a base flange 11 which may be secured to the floor with lag screws or the like. A top casting 12 is adapted to rest upon the frame casting 10 and is secured thereto by the bolts 13. Thus, a complete machine frame is provided to support and house the working parts of the machine.

The central portion of the top casting 12 is provided with a bore 14 into which is pressed a bearing bushing 15. This bearing bushing guides the spindle 16 and aligns therewith the hollow last supporting pin 17 which is secured to the top casting by means of the screws 18.

The last L upon which is mounted the shoe S, and all lasts intended for use with the machine are provided with a fastener receiving recess in the form of a metal last thimble T having two diameters so as to provide a shoulder to engage with the upper end of the last pin 17 and to take the clamping pressure when the heel H is clamped to the shoe as hereinafter described. On all lasts and as shown in Fig. 4, the shoulder of the last thimble is located a fixed distance D away from the heel seat of the last and, as will be later understood, this allows the heel attaching screw F to be driven a definite depth into the shoe and heel regardless of the size of the shoe or the height of the last upon which the shoe is mounted.

The heel clamping device comprises a heel engaging member 19 which is swingably mounted upon the pivot ends of the screws 20 which are threaded into U-shaped end 21 of the arm 22. The other end of the arm 22 is riveted at 23 to a lever 24 which fits within and is pivoted at 25 to the bifurcated head 26 of a plunger 27 which is freely movable in a bore 28 formed in the supporting bracket 29 attached by screws 30 to a boss 31 depending from the top casting 12.

The plunger 27 has a portion 32 of reduced diameter which passes through a hole 33 formed in line with the bore 28 and a compression spring 34, which surrounds the reduced diameter of the

plunger, serves to upwardly bias the plunger 27, the lever 24 and its associated parts.

The nut 35 serves to limit the extent that the plunger 27 can be raised under the influence of the spring 34.

The horizontally disposed end 36 of the lever 24 is bifurcated to straddle the spindle 16 and each leg of the lever is pivotally joined to a treadle rod connector 37 by the clevis pins 38. The upper ends of the treadle rods 39 are screw threaded into the connectors 37 and the lower ends are threaded into the clevises 40 which are pivotally connected to a rod 41 extending from the treadle lever 42. The treadle lever is pivoted to a shaft 43 held by brackets 44 which are secured to the base casting 10 by the bolts 45.

The treadle lever 42 is held in the upward position by a spring or counterweight (not shown) so that the arm 22 carrying the heel engaging member 19 is held in a rearward position, as indicated by dot and dash lines in Fig. 1, leaving the last pin 17 unobstructed to facilitate the placement of the last and shoe upon it.

As more clearly shown in Fig. 7, the upper end 25 of the spindle 16 has a portion 65 of reduced diameter which is threaded to receive a mating threaded portion formed in the head of a wood screw F which the operator screws to the spindle while the spindle is not rotating. After the wood screw 26 has been threaded to the spindle, the last L is placed in position upon the last pin 17. The operator then locates the heel H and depresses the treadle 42 which causes the arm 22 to swing into the position shown in Fig. 1, and the heel engaging member to contact the heel. Further depression of the treadle overcomes the upward bias of the spring 34 and the complete clamping unit moved downwardly to firmly clamp the heel to the shoe.

40 The lower end of the spindle 16 is journalled in a bearing 46 formed in a boss 47 depending from the support bracket 29 and a pulley 48 is keyed to the lower end of the spindle.

The spindle is adapted to be rotated by the belt 49 which is driven by a pulley 50 secured to an electric motor 51 attached to the base casting 10 by the bolts 52.

A worm 53 is keyed to the central portion of the spindle 16 and is held in place and prevented from moving longitudinally of the spindle by the collars 54 and 55 against which the inner races of the ball bearing 56 and 57 are jammed by the lock nuts 58 and 59.

The outer races of the ball bearings fit within 55 the vertical bores formed in the gear housing 60 which is forced to partake of any reciprocating movement of the spindle due to the outer race of the ball bearing 57 being locked against the shoulder 61 of the housing by the cap 62.

60 The gear housing 60 is prevented from rotating with the spindle 16 by a key 63 which is formed integral with the housing and which fits and slides in a spline 64 formed in the supporting bracket 29.

65 The gear housing 60 is provided with horizontally extending bores in which is journalled a shaft 66 having keyed thereto a worm wheel 67 which meshes with the worm 53 on the spindle 16. The shaft 66 extends from each end of the gear housing and the cranks 68 and 69 are secured to the shaft extensions by the set screws 70 and 71. With this construction, the cranks 68 and 69 revolve as long as the spindle 16 is rotating.

Referring now to Fig. 3, the supporting bracket 75 29 is provided with extension arms 72 and 73 ter-

minating in vertically extending bosses 74 and 75. A lever 76, having a closed crank pin engaging slot 77, is pivotally connected to the boss 74 by the pivot screw pin 78. Another lever 79, having an open crank engaging face 80, is pivotally connected to the boss 75 by the pivot screw pin 81. A link 82 is pivoted at one end to the lever 76 by the shoulder screw 83 and at its other end to the lever 79 by the shoulder screw 84. Thus, movement of the link 82 moves both levers.

A bracket 85 having upstanding ears 86 and 87 is secured by screws 88 to the central portion of the link 82. A rod 89 is rotatably mounted in holes formed in the ears of the bracket 85 and a lever 90 located between the ears of the bracket is set screwed to the rod and prevents the rod from being withdrawn from the bracket. A hand knob 91 is secured to the end of the rod 89 and is adapted to be grasped by an operator.

The end of the lever 90 remote from the rod 89 is biased upwardly by a spring 92 until it strikes against the stop nuts 93 screwed to a stud 94 threaded into the link 82.

Normally, the rod 89 is kept in a central position by the plungers 95 and 96 which are biased towards each other by the springs 97 and 98. The plungers are guided by the bushings 99 and 100 which are held to the brackets 101 and 102 secured to the base casting 10 by screws 103.

In operation of the machine, after a wood screw has been threaded to the upper portion 65 of the spindle and the shoe and heel have been located and clamped together as previously described, the operator grasps the hand knob 91 and rotates it in a clockwise direction as he moves the knob laterally to the left as viewed in Fig. 3. Such movement of the hand knob causes the lever 90 to rock with the rod 89 until it presses upon the plunger 104 of a micro-switch 105 (Figs. 2 and 11) which closes an electric circuit to energize the holding coil 106 of a magnetic contactor 107 which in turn energizes the motor 51 and causes it to rotate the spindle 16 in a screw driving direction. Also, as the hand knob is moved laterally to the left, the link 82 is moved causing the closed slot 77 of the lever 76 to engage with the now revolving crank 68, as shown in Fig. 4, and the complete spindle 16 and gear housing 60 is reciprocated upwardly at a rate which is less per revolution of the spindle than the lead or pitch of the wood screw thread on the wood screw F. This causes the wood screw F to bore a lead hole into the heel seat of the shoe S and into the heel H to a depth determined by the throw of the crank 68 which is equal to approximately one-half of the length of the wood screw F. Fig. 5 shows the spindle reciprocated upwardly to bore the lead hole.

The operator continues to keep the hand knob in a rotated position allowing the motor to constantly rotate the spindle, and, after the crank 68 has reciprocated the spindle downwardly to its initial position, which withdraws the wood screw from the shoe and heel and allows the chips to be cleared from the screw thread and the lead hole formed thereby as shown on an enlarged scale in Fig. 7, the hand knob 91 is moved laterally to the extreme right to disengage the closed slot 77 of the lever 76 from the crank 68 and to allow the lever 79 to move to bring the open face 80 thereof under the crank pin 69 as shown in Fig. 6.

As the crank 69 is still rotating, the spindle 16 is again reciprocated upwardly by virtue of the crank pin acting against the face 80, and reciprocation of the spindle continues until the wood

screw F enters the lead hole formed in the heel H and engages with and threads into the material of the heel H. As soon as the wood screw threads engage with the heel material, the lead of the wood screw thread determines the rate at which the spindle reciprocates. This is possible due to the lead of the wood screw thread being greater per revolution of the spindle than the rise afforded by the rotating crank pin 69.

10 When the wood screw F has been driven to the desired depth into the heel H, rotation of the spindle is reversed by means of the reversing switch 108 which is actuated by the collars 109 and 110 attached to a rod 111 threaded to and locked by the nut 112 to a bar 113 which is secured by the screw 114 to an arm 115 extending from the cap 62 which serves to lock the ball bearing 57 in place and which is reciprocated with the gear housing 60.

20 Fig. 8 shows the spindle 16 reciprocated to its uppermost position and the screw driven to its final depth into the heel H.

Reversing the rotation of the spindle 16 unscrews the spindle from its threaded connection 25 with the wood screw F as shown on an enlarged scale in Fig. 9, whereupon, the spindle falls by gravity to its lowest position as shown in Fig. 1 and the reversing switch 108 is restored to its original position.

30 After the spindle has been unscrewed from its connection with the wood screw the operator releases the hand knob 91 and the knob is returned to a central position by the plunger 95. The spring 92 moves the lever 90 away from its contact with the switch 105 causing the motor to be de-energized. The heeled shoe is then removed from the last pin 17 and the machine is ready to receive another shoe.

Referring to Fig. 10, there is shown a modified 40 method of securing the wood screw to the spindle. Such modification comprises forming a shallow recess 117 into the end of the spindle 116 and screw threading same to receive the threaded head of the wood screw F.

45 Since certain changes in carrying out the above described method and in the construction set forth, which embody the invention, may be made without departing from its scope, it is intended that all matter contained in the above description 50 or shown in the accompanying drawing shall be interpreted as illustrative and not in a limiting sense.

It is also to be understood that the following 55 claims are intended to cover all of the generic and specific features of the invention herein described, and all statements of the scope of the invention which, as a matter of language, might be said to fall therebetween.

Having described my invention, what I claim 60 as new and desire to secure by Letters Patent, is:

1. A machine for driving wood screws, comprising 65 work holding means, a spindle reciprocable towards a work piece held by said holding means, means for securing a wood screw to the end of said spindle, means for rotating said spindle in a screw driving direction, means for reciprocating said spindle towards said work piece at a rate which is less per revolution of said spindle than the lead of the thread of the wood screw secured thereto until said wood screw has bored a lead hole into 70 said work piece, means for allowing said spindle to reciprocate at a rate corresponding to the lead of the thread of said wood screw until said wood screw is driven into said work piece to the desired depth, and means for releasing said wood

screw from said spindle, and for returning said spindle to its original position.

2. A machine for driving wood screws, comprising work holding means, a spindle reciprocable towards a work piece held by said holding means, means for securing a wood screw to the end of said spindle, means for rotating said spindle in a screw driving direction, means for reciprocating said spindle towards said work piece at a rate which is less per revolution of said spindle than the lead of the thread of the wood screw secured thereto until said wood screw has bored a lead hole into said work piece, means for reversing the direction of reciprocation of said spindle to withdraw said wood screw from said work piece and to clear the wood chips therefrom, means for again reciprocating said spindle towards said work piece to drive said wood screw into said work piece at a rate determined by the lead of the wood screw thread and to the desired depth, and means for releasing said wood screw from said spindle, and for returning said spindle to its original position.

3. A machine for driving wood screws, comprising work holding means, a spindle reciprocable towards a work piece held by said holding means, said spindle being adapted to have a wood screw secured to the end thereof by a screw thread, means for rotating said spindle in a screw driving direction, means for reciprocating said spindle toward said work piece at a rate which is less per revolution of said spindle than the lead of the wood screw thread of a wood screw threaded to the end of said spindle until said wood screw has bored a lead hole into said work piece, means for allowing said spindle to reciprocate at a rate corresponding to the lead of the wood screw thread until said wood screw is driven into said work piece to the desired depth, and means for reversing the direction of rotation of said spindle to unscrew said wood screw from said spindle and to allow said spindle to return to its original position.

4. A machine for driving wood screws, comprising work holding means, a spindle reciprocable towards a work piece held by said holding means, said spindle being adapted to have a wood screw secured to the end thereof by a screw thread, means for rotating said spindle in a screw driving direction, means for reciprocating said spindle toward said work piece at a rate which is less per revolution of said spindle than the lead of the wood screw thread of a wood screw threaded to end of said spindle until said wood screw has bored a lead hole into said work piece, means for reversing the direction of reciprocation of said spindle to withdraw said wood screw from said work piece and to clear the wood chips therefrom, means for again reciprocating said spindle towards said work piece to drive said wood screw into said work piece at a rate determined by the lead of the wood screw thread and to the desired depth, and means for reversing the direction of rotation of spindle to unscrew said wood screw from said spindle and to allow said spindle to return to its original position.

5. A machine for securing heels to shoes on lasts having screw receiving recesses therein, comprising a frame, a hollow last supporting pin mounted upon said frame, means for clamping a heel to a shoe having its last mounted upon said supporting pin, a screw driving spindle guided in said frame and passing through said hollow last supporting pin, said screw driving spindle being reciprocable towards the heel clamped to said shoe and having means for securing a wood screw to end thereof, means for rotating said spindle

in a screw driving direction, means for reciprocating said spindle at a rate which is less per revolution of said spindle than the lead of the thread of a wood secured thereto until a lead hole is bored into said heel, means for allowing said spindle to reciprocate at a rate corresponding to the lead of said wood screw thread until said wood screw is driven deep enough into said heel to secure it to said shoe, and means for releasing said wood screw from said spindle and for allowing said spindle to return to its original position.

6. In a heel attaching machine, the combination comprising a frame, a hollow last supporting pin, means for clamping a heel to a shoe and last mounted upon said last supporting pin, a reciprocable screw driving spindle guided in said frame and passing through said hollow last supporting spindle, means for securing a wood screw to the end of said spindle, means for rotating said spindle in a screw driving direction, means for reciprocating said spindle towards said shoe and heel to drive a wood screw secured thereto part way into said heel, means for reversing the direction of reciprocation of said spindle to withdraw said wood screw from said heel, and means for thereafter again reciprocating said spindle to drive said screw into said heel to a depth required to firmly secure said heel to said shoe, for releasing said screw from said spindle, and for allowing said spindle to return to its downward position.

7. A machine for securing heels to shoes on lasts having screw receiving recesses therein, comprising a frame, a hollow last supporting pin mounted upon said frame, means for clamping a heel to a shoe having its last mounted upon said supporting pin, a screw driving spindle guided in said frame and passing through said hollow last supporting pin, said spindle being reciprocable towards the heel clamped to said shoe and having its end provided with a screw threaded portion to which the head end of a wood screw can be threaded, means for rotating said spindle in a screw driving direction, means for reciprocating said spindle towards said heel at a rate which is less per revolution of said spindle than the lead of a wood screw thread of a wood screw threaded thereto until a lead hole has been bored into said heel, means for reversing the direction of reciprocation of said spindle to withdraw said wood screw from said heel and to clear the wood chips therefrom, means for again reciprocating said spindle towards said heel and for allowing it to drive said wood screw to the depth required to firmly attach said heel to said shoe, and means for reversing the rotation of said spindle to unscrew it from its threaded connection with said wood screw and for allowing said spindle to return to its original position.

8. In a heel attaching machine, the combination comprising, a frame, a hollow last supporting pin mounted on said frame, means for clamping a heel to a shoe on a last supported by said pin, a housing slidable on said frame, a screw driver spindle journaled in said housing, one end of said spindle extending through said hollow last supporting pin and having a screw threaded portion to receive a correspondingly threaded portion in the head of a wood screw, a shaft journaled in said housing and extending at right angles to said spindle, gearing connecting said shaft and said spindle, a crank on each end of said shaft, means for engaging the crank on one end of said shaft to cause said hous-

ing and spindle to reciprocate towards the heel clamped to said shoe at a rate which is less per revolution of said spindle than the lead of the wood screw thread of a wood screw threaded thereto until a lead hole has been bored into said heel and then to reverse reciprocation of said housing to return said spindle with the wood screw attached thereto to its original position, means for engaging the crank at the other end of said shaft to cause said housing and spindle 10

to again reciprocate towards said heel to drive said wood screw to the desired depth in said heel at a rate determined by the lead of the wood screw thread, and means for reversing the direction of rotation of said spindle to unscrew said wood screw from its threaded connection with said spindle and for allowing said spindle and housing to return to their original position.

EDWARD F. SMALL.
